H. J. MEGLEY

MOLDING MEANS FOR TYPE CASTING MACHINES AND THE LIKE

Filed Aug. 28, 1920

UNITED STATES PATENT OFFICE.

HARLEY J. MEGLEY, OF CHICAGO, ILLINOIS.

MOLDING MEANS FOR TYPE-CASTING MACHINES AND THE LIKE.

Application filed August 28, 1920. Serial No. 406,539.

My invention relates to type molding means for type casting machines and the like and is concerned particularly with the provision of an improved liner for association therewith.

Liners of this general description are positioned between the base and cap members of the mold, between which and the opposed ends of the liners a fused or molten metal is run into a line of assembled matrices to produce a cast, slug or type line. The slug is then ejected by an ejector blade, projected into engagement with the inner edge of the slug or cast and thence through the space bounded by the opposed faces of the mold base and cap and the opposed ends of the liners. In that proper positioning of the liners is essential because a distorted cast will be the result of any discrepancy, suitable cooperative engagement between the liner and mold is provided for properly positioning the liner laterally and longitudinally therein. Frequently, the ejector blade is of greater width than the space between the liners or is so positioned through failure to change or adjust the width or positioning of the blade to conform to a change in length of the slug as the blade is projected to eject slugs of various lengths that upon projection of the blade the liner is engaged with the result that either the shank of the liner or the cooperative positioning connection between the liner and the mold is distorted or the projecting lip at the corner of the liner for positioning the adjacent edge of the cast is broken off. Heretofore, in either event, it has been necessary to replace the distorted liner with an entirely new one. This has occasioned considerable expense in that the liners with their positioning means for engagement with the mold are quite expensive.

It is the object of my invention to provide a simple, effective, inexpensive and improved liner comprising a head portion having positioning means for engagement with the mold and an inexpensive shank portion having jointed connection with the head portion, of such formation that any distortion will be confined to the shank portion of the liner the replacement of which shank portion in connection with the same head portion is far less expensive than is replacement of the entire liner as has been necessary heretofore. The features of my

invention are, therefore, that I provide a two-piece liner and that I confine any distortion to the less expensive of the two pieces. The particular formation shown for accomplishing these features is, of course, subject to modification, the one illustrated showing a type which I have found to be satisfactory.

I still further aim to provide shank portions of various lengths for use with a single head portion whereby slugs or type lines of various lengths may be had by replacing the shank portion of the liner with a shank portion of the desired length. A set of inexpensive liner shanks of various lengths thereby supplants the set of complete liners (each having positioning means for engagement with the mold) of the prior art. A further feature of the invention is that the utility of the shank portions of the liner may be increased by shortening the distorted shanks and using them again.

These and other features of my invention will appear from the following detailed description and the claims taken with an inspection of the accompanying drawings which illustrate a particular embodiment of my invention.

Referring to the drawings:

Figure 1 is a front elevational view of the mold disk of a linotype machine, showing the type molds clamped in place;

Figure 2 is a plan view of the base member of a type mold (taken substantially on the line 2-2 of Figure 1) showing a liner embodying my invention positioned thereupon;

Figures 3 and 4 are perspective views of the shank and head portions respectively of the liner shown in Figure 2; and

Figure 5 is a longitudinal sectional view of a modification.

Referring to the drawings, the mold disk 1 is provided with the usual openings in which the type molds 2 are mounted. The disk 1 may be rotated in the usual or any preferred manner as through an annular gear 3 encircling the periphery thereof and secured thereto.

The molds 2 comprise base members 4 attached as through suitable bolts 5 to the mold disk 1. Posts 6 projecting upwardly from the opposite ends of the base member 4 (Figure 2) engage in cooperating grooves (not shown) in the associated cap members

7 assuring proper relative positioning therebetween. With the liners arranged between the opposed faces of the base member 4 and the cooperating cap member 7 of the mold 5 as will be hereinafter described, the cap member is clamped securely in place by means of set screws 8 (Figure 1) threaded through the mold disk 1 and into engagement with the arcuate edge of the cap member.

The liner with which this invention is particularly concerned comprises a relatively short head portion 9 and a cooperating shank portion 10. The under surface of the head portion 9 is provided with a transverse ridge 11 adapted for cooperation with a groove 12 provided transversely across the upper face of the base member 4 of the mold to position and maintain the proper longitudinal positioning of the liner. In addition to this groove and ridge engagement between the mold and liner head 9, the head 9 is provided with a transverse slot 13 for cooperation with a short pin 14 extending upwardly 20 from the upper surface of the base member 4, limiting the transverse movement of the liner head across the upper face of the base member of the mold and assuring proper lateral positioning of the liner.

30 The outer end of the shank portion 10 of the liner is mortised as shown at 15 for the reception of the adjacent tenoned end 16 of the liner head 9. Thus the head and shank portions of the liner are joined in such manner that separation is impossible, except by relative movement in the direction of their thickness. The opposite end of the shank portion 10 of the liner is provided with a projecting lip 18 for positioning the adjacent edge of the cast or slug, as well understood by those skilled in the art. The lip 18 at the same time notches the corner of the slug to prevent the formation of a bur. The usual liner 19 is positioned adjacent the opposite end of the upper face of the base member 4 of the mold through cooperating ridge and groove and slot and pin or other suitable engagement. A two-piece liner of the type with which my invention 40 is concerned might even be provided at this end of the mold under certain conditions.

Upon arranging the liner between the base and cap members of the mold, the mold is secured to the mold disk 1 as hereinbefore set out. A line of matrices is then assembled as well understood by those skilled in the art, whereupon the fused or molten metal is run between the base and cap members and the opposed ends of the shank portion 10 and the liner 19 and into the line of assembled matrices to produce a cast, slug or type line. The disk 1 is thereupon revolved from casting position to ejecting position whereupon an ejector blade 22 is projected by suitable ejecting mechanism asso-

ciated with the machine into engagement with the inner edge of the slug or cast 20 produced, forcing the same out through the space bounded by the mold base and cap member and the opposed ends of the liners. 70

Should the liner be engaged by the ejecting blade in ejecting the slug as through failure to change the width or adjust the position of the blade to conform to a change in length of the slug, one prong of the 75 mortised end 15 of the shank portion 10 of the liner will be bent back as shown in dotted lines at 21 in Figure 2. Distortion of the liner head 9 or the positioning ridge 11 carried thereby which distortion has been 80 a considerable practical difficulty heretofore in the art is thus effectively prevented. The liner head 9 carrying the liner positioning means is never damaged, the distortion is confined to the shank 10. If the prong is 85 broken off, a new shank is replaced in connection with the same head at a slight expense. If the prong is simply bent back as shown, it might be even bent back into place and the shank portion of the liner used 90 again, subsequent engagement by the ejector blade in all probability resulting in complete rupture of the prong.

By providing shank portions 10 of various lengths for use with the same head portion 9, slugs or type lines of various lengths may be had by replacing the shank portion with a shank portion of the desired length. A set of inexpensive liner shanks of various lengths thereby supplant the set of complete 100 liners of the prior art.

Upon rupturing or breaking off the mortised end of the shank 10, the end can be easily evened off and mortised for further use when a shorter liner is desired in producing a type line of greater length. 105

The particular jointed connection between the head and shank portions of the liner shown is, of course, subject to modification, the essential feature being that the jointed connection is such that any distortion is confined to the less expensive of the two liner pieces.

In the modification shown in Figure 5, the cooperating edges of the mortised and tenoned ends respectively of the head and shank portions 9' and 10' of the liner are beveled as shown at 25. The tenoned end of the head 9' is arranged within the mortised end of the shank 10' whereupon the cooperating beveled edges are forced securely into engagement. Thus while in effect a solid one piece liner is thereby produced any distortion will still be confined to the shank portion 10' substantially as set out in connection with Figures 3 and 4. A distorted shank is readily replaced with another shank forced into engagement with the beveled edge of the mortised end of the head 9'. 115 120 125 130

I contemplate confining any distortion to the shank portion of the liner by weakening the same at a point other than at the jointed connection with the head portion.

* I claim:

1. A liner, comprising a relatively expensive head having a transverse slot for engagement with the mold pin and a transverse rib for engagement with the mold groove, a relatively inexpensive shank having one end defining one end of the mold space, said shank being formed independent of the type metal, and of substantially the same thickness as said head to form a substantially uniform mold opening from the space defining end of the shank to the free end of the liner head, and a joint connecting the head and shank of the liner, said joint comprising a dove-tail tenon on the head and a cooperating dove-tail mortise in the adjacent end of the shank, said mortise extending into close proximity to the opposite side edges of the shank to weaken the same so that the liner shank will rupture first to preserve the head upon engagement of the liner by an ejector.
2. A liner comprising a relatively expensive head having a transverse slot for engagement with the mold pin and a transverse rib for engagement with the mold groove, a relatively inexpensive shank having one end defining one end of the mold space,

said shank being formed independent of the type metal and of substantially the same thickness as said head to form a substantially uniform mold opening from the space defining end of the shank to the free end of the liner head, and a joint connecting the head and shank of the liner, said joint comprising a dove-tail tenon on the head and a cooperating dove-tail mortise in the adjacent end of the shank, said mortise extending into close proximity to the opposite side edges of the shank to weaken the same so that the liner shank will rupture first to preserve the head upon engagement of the liner by an ejector.

3. A liner comprising a head having positioning means for engagement with a mold and a supplementary shank, a joint connecting said shank and head, said joint permitting replacement of the shank and continued use of said head with new shanks, said head and shank being of substantially the same thickness and the cross sectional area of the shank adjacent the joint being less than the adjacent cross sectional area of the head to weaken the shank at the joint so that the shank will rupture first to preserve the head upon engagement of the liner by an ejector.

In witness whereof I hereunto subscribe by name this 25th day of August, 1920.

HARLEY J. MEGLEY.
